FOUNTAIN COMB

Alfred F. Taborski, Bradford, Pa.

Application March 28, 1940, Serial No. 326,474

2 Claims. (Cl. 132—13)

This invention relates to an improved fountain comb.

One object of the invention is to provide a fountain comb which will be particularly effective for treating dandruff and other scalp ailments.

Another object of the invention is to provide a fountain comb having a body formed with a pair of longitudinally extending channels which are separated by an intermediate wall and which channels communicate with openings formed in certain of the teeth, which depend from the body, said openings leading fluid from the channels, through the teeth and onto the scalp.

A further object of the invention is to provide a device of this character wherein one of the channels employed will be particularly useful for receiving liquid shampoo or medicament and wherein the other of the channels will be adapted for receiving water.

And as a still further object, the invention seeks to provide a fountain comb having relatively large and relatively small teeth, the relatively large teeth having openings communicating with the channel adapted for carrying liquid and the relatively small teeth having openings communicating with both of the channels, the openings in the teeth being separated throughout the major portions of their lengths.

And another object of the invention is to provide a device of this character wherein means are employed for permitting ready connection of the comb to a source of shampoo liquid and to a source of water.

Other objects of the invention not pointed out hereinbefore will become apparent during the course of the following description.

My invention is illustrated in the accompanying drawing, wherein:

Figure 1 is a side elevation of my improved fountain comb.

Figure 2 is a longitudinal sectional view on the line 2—2 of Figure 1 looking in the direction of the arrows,

Figure 3 is a vertical sectional view on the line 3—3 of Figure 1,

Figure 4 is a vertical sectional view on the line 4—4 of Figure 1.

Figure 5 is a detail perspective view showing the fountain comb and flexible means leading from the channels thereof for connection to liquid sources, one of said liquid sources being shown.

Figure 6 is an elevation showing a container which is connected with the flexible tube 15.

Figure 7 is a detail end view showing the slideable closure employed for closing the channels when the flexible tubes and couplings are removed.

Referring now more particularly to the drawing, wherein like numerals of reference will be seen to designate like parts throughout the various views, the numeral 1 indicates in general the body of my improved comb. The body 1 may be of any suitable design, the design shown being only by way of example. The body 1, as shown in Figure 1, includes a rod 2 which will facilitate handling. As shown in Figures 2, 3 and 4 of the drawing, the body is provided with an enlarged portion 3, which extends throughout the entire length of said body. The enlarged portion 3 is formed with a pair of longitudinally extending parallel channels 4 and 5, said channels being separated by an intermediate wall 6. The wall 6 cooperates with one end of the body 1 to define an end wall 7. The channels are open at their corresponding opposite ends and are provided with couplings 8 and 9 which are preferably exteriorly threaded throughout their respective lengths and are screwed into the end 20 of the body in communicating relation with the channels 4 and 5.

Depending from the body 1 are sets of teeth 10 and 11. The teeth of the set of teeth 10 are relatively large while the teeth of the set of teeth 11 are relatively small. As will be seen by referring particularly to Figures 2 and 4 of the drawing, the teeth of the set of teeth 10 are each bored throughout their respective lengths to define passages 12, said passages communicating with the channel 5 and with the free lower end of said teeth. The teeth of the set of teeth 11 are bored to define passages 13 and 14. The passage 13 of each tooth communicates with the channel 5 while the passage 14 of each of said teeth communicates with the channel 4. It will now be understood that a liquid outlet is provided from the channel 4 only through the small teeth 11. However, both the small teeth and the large teeth provide a liquid outlet from the channel 5. As seen in Figure 6, the coupling 8 is to be connected, by means of a flexible tube 15, to a container 16, which will contain shampoo, medicament or the like. The coupling 9 is connected, by a flexible tube 17, to a water faucet 50 or other source of water.

It should be understood that the device will lend itself particularly well for use by a person taking a bath. If the device is used under these conditions, the container 16 may be hung on a 55

shower curtain supporting rod so that adequate flow will be assured. The water connection may be, of course, conveniently made to the faucet.

When the device is in use, it is only necessary to permit the medicament to flow from its container and the water to flow from the faucet, either at the same time, or at different times, for cleansing or medicating the scalp. It is desired particularly to point out that, inasmuch as the only outlet from the channel 4 is through the relatively small teeth 11, there will be no waste of shampoo liquid, as would be the case were the relatively large teeth provided with passages communicating with the channel 4. It is desired also to point out that the wall 6 is extended downwardly into the teeth 11, throughout substantially their entire lengths, for preventing mixing of the liquids before reaching the scalp. This construction assures full effectiveness in use for the liquids. Moreover, the extended wall, which is indicated at 18, for sake of convenience, provides reinforcement for the relatively small teeth.

Attention is directed to the fact that, while the channels 4 and 5 are shown as being circular in shape, they may be square, or any other shape, if so desired.

In Figs. 1 and 7 of the drawing, the closure employed is seen more in detail. The closure is indicated generally at 25 and includes a plate 26 having a slotted tongue 27 thereon. A stud 28 is mounted on a flat surface 29, which flat surface is formed by anchoring the end tooth adjacent the open ends of the channels. A lug 30, for manual engagement, is mounted on the plate 26. It will be seen that, when the couplings 8 and 9 are removed, the closure 25 may

be shifted for closing the channels and preventing admission of dirt to within the channels.

Having thus described the invention, what is claimed as new is:

1. In a fountain comb, a body having sets of teeth, certain of said sets of teeth being relatively large and certain other of said sets of teeth being relatively small, said body having channels, a wall separating said channels, said relatively large teeth having passages communicating with one of the channels, said relatively small teeth having pairs of passages communicating with both of the channels, means connecting one of said channels with a source of scalp treating fluid, and means connecting the other of said channels with a source of water, said scalp treating compound flowing through the passages in the small teeth to contact the scalp and the water flowing from the passages in both the large and small teeth for contacting the scalp.

2. In a fountain comb, a body having sets of integral teeth depending therefrom, said body having channels, passages formed in one of the sets of teeth and communicating with one of the channels, pairs of passages formed in the other of said sets of teeth and communicating with both of the channels, and means carried by one of the teeth of the first-mentioned set of teeth and movable for closing the channels to prevent fluid flow therethrough, said means comprising a closure including a plate having a slotted tongue, a stud carried by the tooth of the set of teeth supporting said means and extending through the slot of the slotted tongue, and a lug on the plate for manual engagement.

ALFRED F. TABORSKI.
